UNITED STATES PATENT OFFICE.

EDGAR H. WILSON, OF CHARTIERS TOWNSHIP, ALLEGHENY COUNTY, AND WILLIAM F. CLARK, OF CORAOPOLIS, PENNSYLVANIA.

RENEWABLE FUSE.

1,220,384.

Specification of Letters Patent. Patented Mar. 27, 1917.

Application filed November 3, 1914. Serial No. 870,046.

To all whom it may concern:

Be it known that we, EDGAR H. WILSON and WILLIAM F. CLARK, both citizens of the United States, and residents, respectively, of Chartiers township, Allegheny county, Pennsylvania, and Coraopolis, Allegheny county, Pennsylvania, have invented a new and useful Renewable Fuse, of which the following is a full, clear, and exact description, reference being had to the accompanying drawings, forming part of this specification, in which:

Figure 1 is a side elevation partially in section of one form of our improved renewable fuse.

Fig. 2 is a similar view at right angles thereto.

Fig. 3 is a perspective view of the inclosing case.

Fig. 4 is a perspective view of one of the fuse clamping members.

Fig. 5 is a sectional view of a modified form of the device, and

Fig. 6 is a similar view at right angles thereto.

This invention relates to an improvement in renewable electrical fuses, and is designed to provide a cheap and efficient device, which can readily be made and assembled, and which can also be readily taken apart to renew the fuse after it has been blown. Another object of our invention is to provide a device of this character in which a fuse having a greater cross sectional area than the predetermined fuse cannot be used.

The precise nature of our invention will be best understood by reference to the accompanying drawings, which will now be described, it being premised that various changes may be made in the details of construction, and in the general arrangement of the parts without departing from the spirit and scope of our invention as defined in the appended claims.

Referring to the accompanying drawings the reference character 2 designates a non-conducting tube or casing which is provided with oppositely disposed slots 3 at each end thereof. As the connecting members on opposite ends of the device are the same, we will only describe the connections at one end. 4 designates plates or clamping members which may be milled along their faces, as indicated at 5, the width of the milled recesses being equal to the width of the fuse

ribbon to be used in the particular fuse device. These two members 4 are placed in the slots 3, the length thereof being approximately equal to the diameter of the casing 2, and interposed between the members 4 and seated within the recesses in said members is a fuse strip or ribbon 6. 7 is a cap having an annular flange 8 which surrounds the tube 2, the length of the flange 8 being great enough to extend beyond the slots 3. Connected to the cap 7 is a spring clamp 9 which straddles the clamping members 4 to hold them in contact with the fuse strip 6. The slot between these clamping members is milled to a gage, and the thickness of the members 4 is gaged so that only a predetermined thickness of fuse ribbon can be clamped between the several parts. In other words, the recesses 5 provide means for preventing a ribbon having a greater width than the predetermined width from being used, while the clamping device 9 and the plates 4 prevent the use of a ribbon of greater thickness than the predetermined fuse for the device. Extending upwardly from the cap 7 is a terminal member 10, which may be of any desired form for securing the device to the terminals to be connected thereby.

In Fig. 1 we have shown the end cap 7 held in position on the tube 2 by means of a spring catch 11, while the other end cap 7 is held in position by means of a screw 12.

The device is assembled as follows: The strip of fuse metal is placed between two of the members 4 which are slipped in the slots 3 in one end of the tube or casing 2. The members 4 are then slipped in the slots in the other end of the tube in opposite sides of the fuse, and the caps 7 are then slipped into position over the ends of the tube, the clamping devices 9 forcing the members 4 in contact with the fuse strip. It will readily be understood by those familiar with the art that if a fuse strip having a greater size than the predetermined strip is used the parts cannot be assembled, so that the fuse device can be positively marked to indicate the current it will carry.

In Figs. 5 and 6 we have shown a device somewhat similar to that shown in the figures just described, with the exception that the clamping members 9^a are held in position by means of screw caps 7^a which form the terminals of the fuse device, there being 110

an electrical contact between the clamps 9^a and the caps. The clamps 9^a are slipped over the clamping members and the caps 7^a are then screwed down in place and in contact with said clamps.

The advantages of our invention result from the provision of a fuse device in which the parts are held together by means of frictional clamps which are electrically connected with the terminals of the device.

We claim:

1. A fuse device, comprising a fuse strip, clamping pieces embracing opposite sides of an end portion only of said strip, a removable spring clamp adapted to be forced over the clamping pieces, and means for holding the clamping pieces from moving with the clamp to prevent buckling of the fuse-strip when the clamp is being applied; substantially as described.
2. A fuse device, comprising a casing, a fuse member within the casing, separate clamping pieces embracing opposite sides of an end portion of the strip, the casing having abutments for supporting said pieces and limiting their inward movement in the direction of the length of the strip, and a removable clamping spring fitting over and engaging said pieces, the casing also having a removable cap member which engages and normally secures the clamping spring, said pieces and clamping member being removable at the adjacent end of the casing when the cap member is removed; substantially as described.
3. A fuse device comprising a casing, a fuse strip within the casing, a pair of separate clamping pieces embracing opposite sides of each end portion of the fuse strip, the casing having supports for the end portions of said pieces, a spring clamp embracing each pair of clamping pieces, and means for normally securing said clamps, each pair of said clamping pieces and its clamp being removable from the casing at the adjacent end of the latter; substantially as described.
4. A fuse device, comprising a casing having opposite slots at an end portion thereof, a fuse strip within the casing, clamping members removably seated in said slots and

embracing an end portion of the fuse strip, a clamping device engaging the said members, and means for normally securing the clamping device in place; substantially as described.

5. A fuse device comprising a casing having open slots at an end portion thereof, a fuse strip within the casing, separate clamping pieces removably seated in said slots and embracing an end portion of the fuse strip, and a U-shaped clamping spring embracing and securing said pieces, the casing having a removable cap portion holding said spring in place; substantially as described.

6. A fuse device, comprising a casing having opposite slots at an end portion thereof, a fuse strip within the casing, clamping members removably seated in said slots and embracing an end portion of the fuse strip, and a clamping device engaging the said members, the casing having a removable end closure which confines the clamping device and which also incloses the slotted portion of the casing body; substantially as described.

7. A fuse device comprising a casing having opposite slots in one end portion thereof, a fuse strip, and clamping means removably seated in said slots and embracing an end portion of the strip, said slots being of predetermined width, whereby the clamping means seated therein cannot be spread to receive a fuse strip of greater than a predetermined size; substantially as described.

8. A fuse device, comprising a fuse strip, clamping pieces embracing opposite sides of an end portion only of said strip, a support, a removable spring clamp adapted to be forced over the clamping pieces, and abutments on the support for holding the clamping pieces from moving with the spring clamp and thereby prevent buckling the fuse when the clamp is applied, substantially as described.

In testimony whereof, we have hereunto set our hands.

EDGAR H. WILSON.
WILLIAM F. CLARK.
